UNITED STATES PATENT OFFICE.

EMERSON B. MOSELEY, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

ACCOUNT-REGISTER.

1,122,981.

Specification of Letters Patent. Patented Dec. 29, 1914.

Application filed June 15, 1908. Serial No. 438,622.

To all whom it may concern:

Be it known that I, EMERSON B. MOSELEY, a citizen of the United States, residing at Alliance, in the county of Stark and State 5 of Ohio, have invented certain new and useful Improvements in Account-Registers, of which the following is a specification, reference being had therein to the accompanying drawings.

10 This invention relates to improvements in account registers, and more particularly to that class of account registers in which a series of bill carrying frames is grouped together and mounted so that each individual frame or all of the frames in the series 15 may be moved from a normally vertical position within a casing to a horizontal one, or vice versa.

One of the objects of my invention is to 20 provide in such an account register a series of pivotally mounted bill holding frames constructed and arranged so that they may be readily removed from or inserted into operative position within the casing, without disturbing and removing the pivotal mountings for the said frames, which latter remain at all times in the casing. With 25 my improved construction, from time to time, the series of bill holding frames may 30 be removed from the casing and arranged in compact form for the purpose of storing them in a safe, vault, or other place for safe keeping.

Other objects of my invention will be obvious 35 from the description and disclosure of an account register embodying it which I have herein chosen for the purpose of illustration.

Figure 1 is a front view of an account 40 register embodying my improvements. Fig. 2 is a view showing the casing broken away and the bill holding frames and their supporting members in side elevation. Fig. 3 is a perspective view of the supporting 45 members for the bill holding frames and their supplemental carrying and positioning frame, detached. Fig. 4 is a detail view of an arm of a frame-supporting member. Fig. 5 is a perspective view of the series of 50 bill-carrying frames removed from the casing.

In the drawings, 1 indicates as an entirety a suitable casing or housing. It may be

constructed and arranged in any desired manner. For the purpose of illustration, 55 it is shown as comprising a desk-like base portion 2, having a top 3 formed in two parts, the rear part 3' of which is preferably stationary and has hinged to it the front part 4 to permit ready access to the 60 interior of the base. The rear wall 5 of the casing extends vertically upward, as do the side walls 6 and 7. A cap or top plate 8 may be employed when desired.

9 indicates bill holding frames. These 65 frames in themselves may be of any well known construction. For the purpose of illustration I have shown them comprising a sheet or plate 10, of any suitable material, divided on each side by vertically arranged 70 ribs 10' into a plurality of vertically disposed bill or sales slip receiving sections. Each of these sections is preferably arranged to receive and hold two sets of bills, one above the other. This may be accomplished 75 in any well known manner. For the purpose I have shown clips 11, preferably made of spring metal and suitably secured in position on the frames. The bottom and side edges of the plates 10 may be 80 reinforced in any suitable and well known manner, and for this purpose I have shown U-shaped bars 12, each arranged to receive 85 one of the said plates, the sides and bottoms of the latter being flanged, as indicated at 10^a and 10^b, respectively, and these flanged portions being secured to the adjacent parts 90 of the U-shaped bar, preferably by means of rivets 13. The bill holding frames 9 may be connected together so as to permit the relative lateral as well as the relative longitudinal movement of the frames in the series, and at the same time have the frames associated, so that when they are removed from 95 the casing, they will not become separated, one from the other, and out of place in the series. This connecting together of the frames may be accomplished in any preferred manner. For the purpose of illustration, I have shown at either side of each 100 of the intermediate frames between the front and the rear frame of the series, a pair of links 14, 15, each pivotally connected on a laterally projecting stud 16, carried by the stiffening bar 12 of the frame. The 105 outer end of each link 15 is pivotally con-

nected at 15' to the adjacent end of the adjoining link 14 carried by the next frame in the series. The front and rear frames of the series each carry at either side a single one of these connecting links. Above the laterally projecting studs 16 at the bottom of each frame and also projecting laterally at either side of the frame from the stiffening bar 12, are studs or lugs 17 for a purpose to be hereinafter described.

18 indicates supporting members for the bill holding frames. Each of these frame supporting members 18, in the illustrative construction herein disclosed, comprises a horizontal rod or bar 19, having at either side arms 20 which extend preferably at right angles to the bar 19, and are rigidly secured thereto, and may be formed integrally therewith, if desired. Each of the arms 20 is longitudinally grooved or recessed, as indicated at 21, the walls at the open end of each groove being beveled away, as indicated at 22, to facilitate the introduction of the laterally projecting lugs 16 and 17 on one of the bill holding frames. As many of these frame supporting members 18 are arranged, one behind the other in series, as there are bill holder frames to be supported, and they are preferably held in proper relation to each other in a supplemental frame 23. This latter frame comprises a rear bar 24 adapted to be suitably secured to the back wall 5 of the casing 1, as by means of screws, and forward and downwardly extending side bars 26, having at their front ends feet or brackets 27 which may be suitably secured to the wall 3' of the base, as by means of screws 28. Each of the horizontal bars 19 of the frame supporting members 18 is extended laterally from the arms 20 as indicated at 19' to form pivots or pintles which are rotatably mounted in suitable apertures or bearings 29 in the side bars 26 of the supplemental frame 23.

45 It is often times desirable to counterbalance the bill carrying frames 9 so as to facilitate the operation of the account register as an entirety. For this purpose I have provided the frame supporting members 18 with counterbalancing springs 30. Each transverse bar 19 with the exception of the foremost one in the series, is encircled at one end by one of these coiled springs 30. The outer end of each of these springs is inserted in an opening 31 in the adjacent arm 20. The inner end of the spring is inserted in an opening 32 in a rotatable head 33 loosely mounted on the shaft 19 and between the spring 30 thereon and a washer 34 held 60 from inward movement along the shaft by a pin 35. At one corner of each of its surfaces, each tension adjusting head 33 has an opening or recess 33' arranged to receive one end of a holding arm or positioning piece 36 suitably arranged in the casing.

65

In order to adjust the tension of a spring 30, the head 33 connected to it is rotated on its shaft 19 until the requisite tension is acquired, when the positioning piece 36 is permitted to enter one of the recesses 33' in the head.

On the front frame it is sometimes desired to have more pressure than on the other frames in the series. In order to accomplish this, I have arranged a compound spring 37, one end of which is wound in one direction, and the other end in the opposite direction about the foremost bar 19. The opposite ends of this spring may be secured in any suitable manner to the rod 19, as by means of screws 38. Near the center the spring is straightened, as indicated at 37', to fit into a groove 39' in a tension adjusting head 39 loosely mounted on the rod. This head 39 has its different surfaces recessed at 39^a to receive one end of a positioning and holding piece 40, the other end of which is suitably arranged in the casing.

Assuming that the bill holding frames are removed from the casing 1 and are arranged in the relative position shown in Fig. 5, they may be inserted into working position in the casing simply by directing the lugs 16 and 17 on each frame into the grooves 21 in its respective supporting member 18. The lowermost lug 16 on each frame comes into engagement with the bottom of the groove in the supporting member 18 for the frame, and as the supporting members for the various frames are arranged so that the bottoms of their respective grooves lie one above the other in ascending series from front to rear of the register, the upper edges of the bill carrying frames will project, one above the other, from front to rear of the series, so as to freely expose to view the index numbers 45 on the various frames. The purpose of the lugs 17 is to engage the walls of the grooves 21 at points above their engagement with the lugs 16, so as to preclude the turning of the frames 9 relative to the arms 20 of their respective supporting members.

The operation of the device will be readily understood. With the bill holding frames in the positions shown in Figs. 1 and 2, in order to gain access to any desired leaf, all that is necessary is to grasp the leaf or the one in front of it and pull forward and downwardly. The frames may be returned to their normal position by hand, or the tension springs 30 and 37 may be set so as to cause the frames to swing back into normal position when released.

In order to remove the series of bill carrying frames from the casing, all that is necessary is to grasp the series and lift it upwardly, the lugs 16 and 17 on each frame will be guided out of the supporting member 18 for the frame, and as soon as all of the

frames are free from their supporting frames, the series of bill carrying frames may be lifted out of the casing and arranged in compact form.

5 In order to overcome the frictional resistance between the adjacent edges of adjoining arms 20 of the frame-supporting members, I have provided each of these arms with an anti-friction roller 41 loosely 70 mounted on a stud 42 extending laterally from the arm. The periphery of each of these rollers is adapted to engage with the surface of a cam 43 carried by the adjoining arm 20 of the preceding frame supporting 10 member in the series. The cam surface of each of these cams 43 is low at either end, as indicated at 43', 43^a, and gradually rises between these ends, as indicated at 43^b, so that when the frame supporting members 15 are in vertical position within the casing, the edge of each one of them engages with the adjacent edge of the adjoining member and this is also true when the supporting members are swung down into horizontal 20 position, but between these vertical and horizontal positions, the rollers 41 riding on their respective cam surfaces separate the arms 20 from each other so as to preclude frictional engagement between their edges 25 30 as the bill holding frames are oscillated.

The tension springs 30 and 37 normally tend to swing the frames rearwardly, as viewed in Fig. 2, and the frames with the arms 20 of their supporting members are 35 normally maintained vertically by the combined action of the said tension springs and the engagement of adjacent edges of adjoining arms 20, since, when the edges of two adjoining arms lie in engagement with each 40 other, the two arms are prevented from swinging about their respective pivots.

To those skilled in the art of making account registers, many alterations in construction and widely differing embodiments 45 and applications of my invention will suggest themselves, without departing from the spirit and scope thereof. My disclosures and the description herein are purely illustrative, and are not intended to be in any 50 sense limiting.

What I claim is—

1. An account register comprising a plurality of movable supporting members, each having at either end a longitudinally 55 grooved arm, and a series of bill holding frames, one for each of said supporting members, and each frame having at either side a plurality of lateral extensions arranged to be longitudinally inserted into and withdrawn from the groove in the adjacent arm of the supporting member for said frame.

2. An account register comprising a plurality of movable supporting members, each 60 having at either end a longitudinally

grooved arm, and a series of bill holding frames, one for each of said supporting members, and each frame having at either side a plurality of lateral extensions disposed one above the other and arranged to 70 be longitudinally inserted into and withdrawn from the groove in the adjacent arm of the supporting member for said frame.

3. An account register comprising a plurality of pivotally mounted supporting 75 members, each having at either end a longitudinally grooved arm, and a series of bill holding frames, one for each of said supporting members, and each frame having at either side a plurality of lateral extensions 80 arranged to be longitudinally inserted into and withdrawn from the groove in the adjacent arm of the supporting member for said frame.

4. An account register comprising a plurality of supporting members mounted on independent pivots arranged one behind the other, said members being free to oscillate independently or collectively, a plurality of bill holding frames, one for each of said 85 supporting members, and connections between each frame and its supporting member constructed to permit the ready removal and replacement of the frame.

5. An account register comprising a plurality of supporting members mounted on independent pivots arranged one behind the other in ascending series, said members being free to oscillate independently or collectively, a plurality of bill holding frames, 100 one for each of said supporting members, and connections between each frame and its supporting member constructed to permit the ready removal and replacement of the frame.

6. An account register comprising a series of bill holder frames connected together to permit relative lateral and longitudinal movement of the frames, a movable supporting member for each frame, and connections between each frame and its supporting member constructed to permit the ready removal and replacement of the frame.

7. An account register comprising a series 115 of bill holder frames linked together, a movable supporting member for each frame, and connections between each frame and its supporting member constructed to permit the ready removal and replacement of the 120 frame.

8. An account register comprising a series of bill holder frames hinged together, a pivotally mounted supporting member for each frame, and connections between each frame and its supporting member constructed to permit the ready removal and replacement of the frame.

9. An account register comprising a plurality of pivotally mounted bill carrying 125

- frames, and cams and anti-friction rollers movable with the said frames and arranged to separate the frames and reduce the friction between them when they are oscillated.
- 5 10. In a filing appliance, the combination of a series of leaves, a projecting stud carried by the opposite ends of each leaf, grooved supporting means for said studs, the said supporting means operating to permit the reclining of the leaves from a substantially vertical position to a substantially horizontal position and vice versa, and links pivotally connected to the opposite ends of the leaves for connecting them together.
- 15 11. In a filing appliance, the combination of a series of leaves, a supporting pin projecting laterally from the opposite ends of each leaf near its bottom edge, links between adjacent leaves each pivotally connected at one end to an adjacent pin, and means for pivotally connecting the links between adjacent leaves together, the said projecting pins being adapted for connection with a suitable support whereby the leaves 25 may be swung on an axis relative to each other.
12. In a filing appliance, the combination of a casing, a series of slip holding leaves linked together at their bottom or lower portion, the links of the leaves being pivotally attached together, a pin secured to the opposite ends of each leaf, and supporting means provided with open recesses to receive the said pins.
- 30 13. In a filing appliance, the combination of a casing, a series of slip holding leaves linked together at their bottom or lower portion, the links of the leaves being pivotally attached together, a pin secured to the opposite ends of each leaf, and supporting means provided with stepped open recesses to receive the said pins.
- 35 14. In a filing appliance, the combination of a series of leaves, a supporting pin extending laterally from the opposite ends of each leaf, links connecting adjacent leaves together pivotally connected at one end to an adjacent leaf, and the opposite end of each link pivotally connected to a link of an adjacent leaf, and supporting means having recesses to receive the projecting pins.
- 40 15. A filing appliance comprising a series of bill holding frames linked together, supporting members for said frames, and connections between each frame and said supporting members constructed to permit the ready removal and replacement of the frames.
- 45 16. In a credit cabinet, the combination of a case, a series of credit slip holding leaves linked together at their bottom or lower portion, the links of the leaves pivotally attached together, bearings secured to the leaves, and supports provided with open recesses, said open recesses adapted to receive the bearings, substantially as and for the purpose specified.
- 50 17. In a credit cabinet of the class described, the combination of a casing, a series of credit slip holding leaves provided with credit slip holding clips, said credit slip holding leaves linked together at their bottom or lower ends and provided with bearings, supports provided with stepped open recesses, said recesses adapted to receive the bearings of the credit slip holding leaves, and the links pivoted together, substantially as and for the purpose specified.
- 55 18. The combination of a series of frames of uniform size and shape and provided with projecting rods at their opposite lower ends, means for supporting said rods in stepped relationship and permitting said frames to swing from a substantially vertical to a substantially horizontal position, and links between said projecting rods for connecting said frames together, whereby said frames can be adjusted toward and from each other.
- 60 19. The combination of a series of bill holding frames, means for pivotally supporting said frames in stepped relationship to each other, and co-engaging devices carried by the frames for separating them relatively to each other when operated in groups.
- 65 20. The combination of a series of bill holding frames, means for pivotally supporting said frames in stepped relationship to each other, and cam operated means carried by the frames for separating them relatively to each other during their movement when operated in a group or groups.
- 70 21. The combination of a series of bill holding frames, means for pivotally supporting said frames in stepped relationship to each other, and devices for swinging the frames relatively to each other about their respective pivots during the swinging movements of said frames when operated in groups.
- 75 22. In apparatus of the character described, the combination of a series of bill holding frames, a series of pivoted members, one for each frame, for supporting said frames, means for pivotally supporting said members to swing relative to each other, and means for swinging said frames relatively to each other during their movement when said frames are operated in groups.
- 80 23. The combination of a series of bill holding frames, means for pivotally supporting said frames independently in stepped relationship, permitting them to swing separately or in groups, and means for causing relative swinging movement between the frames during their operation when operated in groups.
- 85 24. The combination of a series of bill holding frames, means for pivotally supporting said frames in stepped relationship, permitting them to swing separately or in groups, and means for causing relative swinging movement between the frames during their operation when operated in groups.
- 90 25. The combination of a series of bill holding frames, means for pivotally supporting said frames in stepped relationship, permitting them to swing separately or in groups, and means for causing relative swinging movement between the frames during their operation when operated in groups.
- 95 26. The combination of a series of bill holding frames, means for pivotally supporting said frames in stepped relationship, permitting them to swing separately or in groups, and means for causing relative swinging movement between the frames during their operation when operated in groups.
- 100 27. The combination of a series of bill holding frames, means for pivotally supporting said frames in stepped relationship, permitting them to swing separately or in groups, and means for causing relative swinging movement between the frames during their operation when operated in groups.
- 105 28. The combination of a series of bill holding frames, means for pivotally supporting said frames in stepped relationship, permitting them to swing separately or in groups, and means for causing relative swinging movement between the frames during their operation when operated in groups.
- 110 29. The combination of a series of bill holding frames, means for pivotally supporting said frames in stepped relationship, permitting them to swing separately or in groups, and means for causing relative swinging movement between the frames during their operation when operated in groups.
- 115 30. The combination of a series of bill holding frames, means for pivotally supporting said frames in stepped relationship, permitting them to swing separately or in groups, and means for causing relative swinging movement between the frames during their operation when operated in groups.
- 120 31. The combination of a series of bill holding frames, means for pivotally supporting said frames in stepped relationship, permitting them to swing separately or in groups, and means for causing relative swinging movement between the frames during their operation when operated in groups.
- 125 32. The combination of a series of bill holding frames, means for pivotally supporting said frames independently in stepped relationship, permitting them to swing separately or in groups, and means for causing relative swinging movement between the frames during their operation when operated in groups.
- 130 33. The combination of a series of bill holding frames, means for pivotally supporting said frames independently in stepped relationship, permitting them to swing separately or in groups, and means for causing relative swinging movement between the frames during their operation when operated in groups.

holding frames, means for pivotally supporting said frames independently in stepped relationship, permitting them to swing separately or in groups, and cam means for causing relative swinging movement between the frames during their operation when operated in groups.

In testimony whereof I affix my signature, in the presence of two witnesses.
